Primary Examiner—Louis S. Zarfas*Attorney, Agent, or Firm*—Nixon & Vanderhye**[57] CLAIM**

The ornamental design for a shoe sole, as shown and described.

DESCRIPTION

FIG. 1 is an illustrative view of a shoe sole showing my new design in a position of use. The broken line showing of the shoe in FIG. 1 is for illustrative purposes only and forms no part of the claimed design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and

FIG. 8 is a perspective view thereof.
